REPRODUCTION OF PRINTED MATTER USING THERMAL NEUTRONS

Ralph F. Lumb, Wallingford, Conn., assignor, by mesne
assignments, to Moore Business Forms, Inc., Niagara
Falls, N.Y., a corporation of Delaware

Filed Feb. 9, 1960, Ser. No. 7,625

14 Claims. (Cl. 250—65)

This invention relates to a method of and mechanism for the reproduction of printed, written, typed or like material and particularly to reproduction of such material in sheet form such, for example, as is commonly done by photographic or similar methods. The invention also relates to a mechanism which may be conveniently employed to carry out this method.

The method is based upon the reaction of thermal neutrons with some substance such as boron or lithium to produce high-energy alpha or beta particles which in turn act upon a sensitized sheet or a sheet of paper or the like bearing a photographic layer of material to produce the image of the copy of printed or written matter upon a master sheet.

In the process a master is first made by written, typing, printing or sketching the material upon a master sheet with inks into which have been incorporated some element such as boron or lithium, for example, with which neutrons from a suitable source will react to produce high-energy alpha or beta particles. In turn these particles will affect the sensitized sheet and produce thereon the necessary sharp image. The mechanism is so constructed as to prevent the generation of harmful radiation so that no special precautions need be taken by the operator in its use. In the preferred form of mechanism herein disclosed a pair of cooperating rolls are employed between which the master sheet and sensitized sheet are fed. One of the rolls is provided at its axis with a source of slow moving neutrons, and this roll is so shielded as to prevent exposure of the operator to harmful radiation. The master sheet is placed in contact with this roll and between it and the other or presser roll is introduced the sensitized sheet to be acted upon by the high-energy alpha or beta particles produced by the boron or other material in the ink on the master sheet to produce the image on the sensitized sheet.

One object of the invention is to provide a new and improved method of reproducing written, typed, printed or sketched materials.

A further object of the invention is to reproduce such materials by a method which includes the production of the material to be duplicated by the use of ink containing a substance which, upon reaction with thermal neutrons, will produce high-energy alpha or beta particles which in turn will effect the production of an image upon a sensitized sheet maintained in close contact with the master sheet.

Still another object of the invention is to provide an improved mechanism for carrying out the described process.

To these and other ends the invention consists in the novel features and combinations of parts to be hereinafter described and claimed.

In the accompanying drawings:

FIG. 1 is a front elevational view, partly in section, of mechanism for reproducing or duplicating printed, typed, written or sketched material, some parts being broken away and shown in section; and

FIG. 2 is a sectional view on line 2—2 of FIG. 1.

To illustrate a preferred embodiment of a mechanism for carrying out my improved process, I have shown in the drawings a casing 10 within which are rotatably mounted a pair of cooperating rolls 11 and 12. These rolls

2

may be provided with suitable pintles 13 and 14 to which are secured respectively the gears 15 and 16, these gears meshing with each other and preferably being so proportioned with respect to the diameter of the rolls to rotate the latter at the same peripheral speeds. The gear 16 may be driven from any suitable source indicated conventionally at 17.

The body 18 of the roll 11, as illustrated, may be conveniently formed of some plastic substance such as polyethylene and provided about its periphery with a cover of some hard material such as "Lucite." At the axis of this roll is located a source of neutrons 20 which may be of any metal suitable for this purpose and which is in rod-like form and is substantially coextensive in length with the roll itself. For example, a mixture of plutonium and beryllium may be placed in a tubular capsule and the capsule sealed to provide this element. The roll 12 may be of any suitable material such as hard or at least firm rubber, for example.

20 An entrance chute 21 is provided for entrance of a master sheet 22 upon which the material to be copied has been placed and a superposed sensitized sheet 23, which sheets are directed into the bite between the rolls. Similarly a discharge chute 24 is provided to receive the 25 master sheet and sensitized sheet from the rolls and discharge them from the machine at the opening 25. The lower wall 26 of the entrance chute as well as the inner wall 27 of the discharge chute and the front portion 28 of the casing between the entrance and discharge chutes 30 are steel clad to afford a boral neutron shield so that the neutron will only strike the sensitized sheet at the time of transfer of the material thereto. The inner ends of the members 26 and 27 approach the rolls closely, but between them there is a minimum gap, through which 35 the rolls engage, to permit the impinging of the neutrons on the master sheet. The member 27 may wipe against the lower roll as shown at 29 to guide the two sheets into the discharge chute. The outer wall of the discharge chute 24 may be continued beyond the casing, as shown 40 at 30, to form a shelf for the discharged copy.

In carrying out the process the copy or material which is to be duplicated will be written, typed, printed or sketched upon a master sheet by the use of an ink into which has been incorporated some element such as boron 45 or lithium, for example, with which the neutrons will interact to produce the high-energy alpha or beta particles. For example, boric acid might be dissolved in standard fountain pen ink, and this ink utilized to make the master sheet which is to be copied.

50 The photosensitive sheet or sensitized paper is then placed in close contact with the master sheet and the two fed in between the rolls 11 and 12 so as to be exposed to the source of neutrons 20. The high-energy alpha or beta particles generated by the neutrons within those portions of the master sheet which have been inked well interact with the sensitized paper to reproduce exactly, on the sensitized sheet, the inscription or image on the master.

55 In this fashion a direct positive can be prepared from the master sheet using standard photographic emulsion as the sensitized sheet. The process may also be used with "Ozalid" paper to produce a negative.

Because of the high ionizing power of alpha particles (approximately 100,000 times that of the photons) and their short range, an extremely dense ionization takes place with each alpha particle. Thus the process may be best accomplished with those materials generating alpha particles upon bombardment with neutrons. Any type of sensitized paper may be employed such as that having a photographic emulsion applied thereto or the previously mentioned "Ozalid" paper.

70 While I have shown and described a preferred embodiment of my invention and a preferred method of carry-

ing out my improved process, the same is not to be limited to all of the details shown but is capable of modification and variation within the spirit of the invention and within the scope of the appended claims.

What I claim is:

1. The method of reproducing printed, written or typed material which comprises placing such material on a master sheet in ink containing a substance which is susceptible of radioactivity and which may later react with neutrons to produce high-energy alpha or beta particles, subjecting one side of said master sheet to the action of neutron radiation to only momentarily produce such particles while producing an image of the material on a sensitized sheet placed on the other side of said master sheet.

2. The method of reproducing printed, written or typed material which comprises placing such material on a master sheet in ink containing a substance which is susceptible of radioactivity and which may later react with neutrons to produce high-energy alpha or beta particles, placing said master sheet between a source of neutrons and a sheet of material sensitive to high-energy alpha or beta particles, and subjecting the material to neutron radiation from said source only while said sheets are superposed.

3. The method of reproducing printed, written or typed material which comprises placing such material on a master sheet in ink containing a substance which is susceptible of radioactivity and which may later react with neutrons to produce high-energy alpha or beta particles, superposing a sheet of sensitized material on said master sheet, passing said sheets between two cooperating closely spaced rolls to hold them flatly together and impinging, on said master sheet, neutrons from a suitable source to obtain on the sensitized sheet an image of the material on said master sheet.

4. The method of reproducing printed, written or typed material as in claim 1 wherein the ink-contained substance is boron.

5. The method of reproducing written, printed or typed material as in claim 1 wherein the ink-contained substance is lithium.

6. The method of reproducing printed, written or typed material which comprises placing such material on a master sheet in ink containing boron, superposing a sensitized sheet on said master sheet and passing said master sheet and sensitized sheet over a source of neutrons to obtain on said sensitized sheet an image of the material on said master sheet while shielding said neutron source except at a position adjacent a small portion of the area of said master sheet.

7. A device for the reproduction of written, printed or typed characters on sheet material which comprises a casing, a pair of closely spaced rolls rotatably mounted therein, means for rotating said rolls and directing sheet material therebetween, and a rod-like neutron source provided at the axis of one of said rolls and extending axially of said one roll.

8. A device for the reproduction of written, printed or typed characters on sheet material which comprises a casing, a pair of closely spaced rolls rotatably mounted therein, means for rotating said rolls and directing sheet material therebetween, a rod-like neutron source provided at the axis of one of said rolls and extending axially of said one roll, and said one roll having a hard outer casing.

9. A device for the reproduction of written, printed or typed characters on sheet material which comprises a casing, a pair of closely spaced rolls rotatably mounted therein, means for rotating said rolls and directing sheet material therebetween, a rod-like neutron source provided at the axis of one of said rolls and extending axially of said one roll, and shielding means surrounding said one roll except in the neighborhood of its close approach to the other roll.

10. A device for the reproduction of written, printed or typed characters on sheet material which comprises a casing, a pair of closely spaced rolls rotatably mounted therein, means for rotating said rolls and directing sheet material therebetween, a rod-like member comprising a neutron source provided at the axis of one of said rolls and extending axially thereof and being substantially coextensive in length with said one roll.

11. A device for the reproduction of written, printed or typed characters on sheet material which comprises a casing, a pair of closely spaced rolls rotatably mounted therein, means for rotating said rolls at substantially equal peripheral speeds, an entrance chute for directing sheet material to the bite between said rolls, a discharge chute for directing sheet material away from said rolls, and a neutron source comprising a metallic substance of rod-like form extending axially of one of said rolls and substantially coextensive in length with said one roll.

12. A device for the reproduction of written, printed or typed characters on sheet material which comprises a casing, a pair of closely spaced rolls rotatably mounted therein, means for rotating said rolls at substantially equal peripheral speeds, an entrance chute for directing sheet material to the bite between said rolls, a discharge chute for directing sheet material away from said rolls, a neutron source comprising a metallic substance of rod-like form extending axially of one of said rolls and substantially coextensive in length with said one roll, and neutron-shielding means embracing said one roll except in the neighborhood of its close approach to the other roll.

13. The method of reproducing printed, written or typed material which comprises placing such material on a master sheet in ink containing a substance susceptible of radioactivity, superposing a sheet of photosensitive material on said master sheet, and rendering said master sheet radioactive substantially only while in contact with the photosensitive sheet by bombarding the master sheet with neutrons from a neutron source.

14. The method of reproducing printed, written or typed material which comprises placing such material on a master sheet in ink containing a substance susceptible of radioactivity, superposing a sheet of photosensitive material on said master sheet, and bombarding the master sheet with neutrons from a neutron source only while the master sheet is in contact with the sensitized sheet.
